UNITED STATES PATENT OFFICE.

HERMANN KEIL, OF ETTINGSHAUSEN, GERMANY, ASSIGNOR TO WILLIAM KEIL, OF NEW YORK, N. Y.

DEVICE FOR HOISTING AND LOWERING LOADS.

Application filed August 29, 1921. Serial No. 496,622.

To all whom it may concern:

Be it known that I, HERMANN KEIL, a citizen of Germany, and a resident of Ettingshausen, Giessen County, Hesse, Germany, have invented certain new and useful Improvements in Devices for Hoisting and Lowering Loads (for which I have filed an application in Germany on July 21st, 1920); and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention is a lifting device for hoisting and lowering loads and the object of the invention is to provide a simple, economical and highly efficient construction adapted, more particularly, for loading and unloading lumber and analogous uses where it is desired to raise relatively heavy weights for relatively short distances. The present invention provides a light and durable construction capable of lifting heavy loads through the application of relatively little power.

The invention embodies, in its preferred practical form, a post-like frame comprising parallel side sections spaced apart at their opposite ends and between these side sections is mounted a winch adapted to be operated by a handle or operating lever which, when the device is not in use, may be positioned in the space between the side sections and entirely within the frame to permit the device to be transported in a most compact condition.

An important feature of the invention resides in a post-like frame between the side sections of which is mounted a winch comprising a winding drum with which is associated a ratchet adapted to be driven by a pawl pivoted for bodily movement about the ratchet and on the same axis of rotation as the ratchet and drum for the purpose of rotating the drum, and this pawl is oscillated about this axis by means of an operating lever pivoted on a different axis and adapted to operate the pawl through greater or lesser leverage as may be required.

Features of the invention, other than those adverted to, will be apparent from the hereinafter detailed description and claims,

when read in conjunction with the accompanying drawings.

In the accompanying drawings,

Figs. 1 and 2 are both side elevations in lifting position.

Figs. 3 and 4 are side elevations with the working lever in its lowest position.

Figs. 5 and 6 are details of the lowering gear with the working lever in its lowest position.

The hoisting device consists of the upright timbers *l* which in connection with the head ties *m* form a post which is fitted with the two axle bolts *o*, *p* in sheet metal fittings *n* for the gearing. The gearing consists of a hoisting roller *k* mounted on the axle bolt *o*, said roller being built as shown with a perforated rim and surrounded by a forked hoop *g* which likewise pivotally swings on the bolt *o*, and carries a driving ratchet *h* pivoted intermediate its ends at *d*. A connecting rod *i* is connected to the hoop *g* and can be connected with the holes of the working lever *f* swinging on the lower bolt *p* according to choice, so that the proper gearing may at once be switched in by setting the lever arm.

To the bolt *p* a pawl *a* is pivotally attached which is pressed on to the perforated rim by a weight *b*, hinged to same in such manner that the latter resting on said pawl shifts the entire center of gravity into the lever arm opposite the pawl *a*, that is, presses the pawl up. A hook *c* is provided on the frame and the weight *b* swings so loosely, that it can be lifted, and by a slight shifting to the side be thrown onto the hook. A catch *r* (Figs. 5 and 6) of the weight *b* is adapted to lie in the path of the working lever *f*, so that when the latter is in the highest position (beginning of lifting), the catch is thrown out of the hook *c* and the pawl *a* is again pressed up to engage the perforations of the lifting roller *k*.

For using the winch, the proper gearing should first be set by means of the connecting rod *i*, whereupon the load is raised by moving the working lever up and down. Hereby the force expended is utilized in the most advantageous manner, as the downward stroke is enhanced by the weight of the body.

For lowering, the weight *b* is laid in the hook *c*, whereupon the working lever *f* is pressed down, so that the pawl *a* thereby

released falls out, whereupon the load is lowered by lifting up the working lever *f*, until the working lever striking the catch *r* releases the weight *b* from the hook *a*, thereby causing the pawl *a* to catch. The pawl *h* is now disengaged and the working lever is then easily lowered without effort.

Having now particularly described and ascertained the nature of my said invention 10 and in what manner the same is to be performed, I declare that what I claim is:

1. A device for hoisting and lowering loads embodying a drum mounted for rotation, a ratchet associated with the drum, a carrier pivoted coaxially of the drum and ratchet, a pawl mounted on the carrier and adapted to cooperate with the ratchet, an operating lever pivoted on an axis, other than the axis of the drum, a link pivoted to 15 the carrier and adapted to be pivotally secured to the operating lever at different distances from the fulcrum of said lever, whereby power exerted through the link upon the carrier by the lever can be varied, a second 20 pawl pivoted on the axis of the fulcrum of the operating lever and weighted to normally engage with the ratchet of the drum for the purpose of precluding inadvertent rotation of the drum, a retainer for supporting 25 the weight of the pawl while the operating lever is being oscillated in one direction to lower a load, and means associated with the weight for automatically disengaging it from its retainer for the purpose of permitting the pawl to re-engage the ratchet 30 of the drum when the operating lever has reached the end of its weight lowering stroke.

2. A device for hoisting and lowering loads embodying a drum mounted for rotation, a ratchet associated with the drum, a carrier pivoted coaxially of the drum and ratchet, a pawl mounted on the carrier and adapted to cooperate with the ratchet, an operating lever pivoted on an axis other than the axis of the drum, a link pivoted to the carrier and adapted to be pivotally secured to the operating lever at different distances from the fulcrum of said lever, whereby power 40 exerted through the link upon the carrier can be varied, a second pawl pivoted on the axis of the fulcrum of the operating lever and weighted to normally engage with the ratchet of the drum for the purpose of precluding inadvertent unwinding rotation of the drum, a retainer for supporting the weight of the pawl, while the operating lever is being oscillated in one direction to lower a load, the said weight on the pawl being provided with a projection adapted to automatically disengage the weight 45 from the retainer for the purpose of permitting the pawl to re-engage the ratchet of the drum, when the lever has substantially reached the end of its weight lowering stroke.

the retainer for the purpose of permitting the pawl to re-engage the ratchet of the drum when the operating lever has substantially reached the end of its weight lowering stroke. 65

3. A device of the character described embodying a winding drum mounted to rotate on a fixed axis, a ratchet associated with the drum, a pawl for actuating the ratchet, a lever fulcrumed on a fixed fulcrum, means associated with the pawl and adapted to be secured to the lever at different distances from the fulcrum of the lever while the lever remains on its fixed fulcrum, whereby power appropriate to the load may be applied from the lever to the drum to effect a step by step rotation of the latter, and a second pawl pivoted on the axis of the fulcrum of the operating lever and weighted to normally engage with the ratchet of the drum for the purpose of precluding inadvertent unwinding rotation of the drum, a retainer for supporting the weight of the pawl, while the lever is being oscillated in one direction to lower the load, and means associated with the weight for automatically disengaging it from its retainer for the purpose of permitting the pawl to re-engage the ratchet of the drum when the lever has substantially reached the end of its weight lowering stroke. 75 80 85 90 95

4. A device of the character described embodying a winding drum mounted to rotate on a fixed axis, a ratchet associated with the drum, a pawl for actuating the ratchet, a lever fulcrumed on a fixed fulcrum, means associated with the pawl and adapted to be secured to the lever at different distances from the fulcrum of the lever while the lever remains on its fixed fulcrum, whereby power appropriate to the load may be applied from the lever to the drum to effect a step by step rotation of the latter, and a second pawl pivoted on the axis of the fulcrum of the operating lever and weighted to normally engage with the ratchet of the drum for the purpose of precluding inadvertent unwinding rotation of the drum, a retainer for supporting the weight of the pawl, while the lever is being oscillated in one direction to lower a load, the said weight on the pawl being provided with a projection adapted to automatically disengage the weight from the retainer for the purpose of permitting the pawl to re-engage the ratchet of the drum, when the lever has substantially reached the end of its weight lowering stroke. 100 105 110 115 120

In testimony that I claim the foregoing as my invention I have signed my name.

HERMANN KEIL.
